UNITED STATES PATENT OFFICE.

PETER J. DOYLE, OF STAMFORD, CONNECTICUT.

DESIGN FOR A CRIBBAGE-BOARD.

SPECIFICATION forming part of Design No. 33,766, dated December 18, 1900.

Application filed November 22, 1900. Serial No. 37,404. Term of patent 7 years.

To all whom it may concern:

Be it known that I, PETER J. DOYLE, a citizen of the United States, residing at Stamford, in the county of Fairfield and State of Connecticut, have invented and produced a new and useful Design for a Cribbage-Board, of which the following is a specification.

My invention is a design for cribbage-boards; and it consists in the shape and configuration illustrated in the accompanying drawing and fully described hereinafter.

The drawing represents a plan view of a cribbage-board embodying my improved design.

The board is of the general rectangular shape shown in the drawing and is formed at its upper end with oppositely-curved edges 1 and 2 and a central projection 3.

The lower end of the board is provided with projecting scrollwork 4.

The board is formed with four longitudinal rows of perforations 5, said rows being parallel, and at the lower end of the board are par-

allel transverse rows of perforations 6. Within the spaces formed by the longitudinal rows 25 of perforations may be printed any preferred matter—as, for instance, a calendar.

Projecting from opposite sides of the board, near the upper end thereof, are arms 7, and adjacent to the opposite end of the board are 30 the oppositely-projecting arms 8.

The leading feature of my design is the relative arrangement shown of the rows of perforations, and the minor features are the oppositely-projecting arms 7 and 8 and the peculiar contour of the ends of the board. 35

I claim—

The design for a cribbage-board herein shown and described.

In testimony whereof I affix my signature 40 in presence of two witnesses.

PETER J. DOYLE.
